UNITED STATES PATENT OFFICE.

LEWIS GIBBS, OF CANTON, OHIO.

DESIGN FOR A POST-HOLE DIGGER.

SPECIFICATION forming part of Design No. 23,072, dated February 13, 1894.

Application filed October 19, 1893. Serial No. 488,649. Term of patent 14 years.

To all whom it may concern:

Be it known that I, LEWIS GIBBS, a citizen of the United States, and a resident of Canton, county of Stark, State of Ohio, have invented and produced a new and original Design for Post-Hole Diggers, of which the following is a full, clear, and exact description, reference being had to the accompanying drawings, making part of this specification.

10 My design relates to a post-hole digger.

In the accompanying drawings, Figure 1, is a perspective view of my design. Fig. 2, is a cross section of the blade.

15 A, denotes the handle socket semi-circular in cross section; B, the handle,—and C, the blade. This blade is approximately semi-circular in cross section, and has its upper edge concave and its lower edge convex, both edges being cut on the same radius.

The leading features, are the handle, the handle socket and the blade semi-circular in cross section having its upper and lower edges concaved and convexed, respectively on a common radius.

Having thus described my invention, what I claim is—

The design for post-hole diggers herein shown and described.

In testimony whereof I have hereunto set my hand this 29th day of September, A. D. 30 1893.

LEWIS GIBBS.
